(57) **CLAIM**

The ornamental design for a motorcycle tire as shown and described.

DESCRIPTION

FIG. 1 is a perspective view of a motorcycle tire showing my new design;

FIG. 2 is a front view thereof, the rear view being a mirror image thereof;

FIG. 3 is a top plan view thereof, the bottom view being identical;

FIG. 4 is a right side view thereof;

FIG. 5 is a left side view thereof;

FIG. 6 is a fragmentary enlarged front view showing the details of the tread portion defined by bracket 6 in FIG. 2; and,

FIG. 7 is a cross sectional end view taken along line 7-7 in FIG. 6.

The broken lines in the drawings illustrate features of a tire that are not being claimed, and form no part of the claimed design. The stippled surface shading represents the recessed portion of the claimed tread groove, having the depth as shown in FIG. 7.
